AUTOMATIC STRIP GRINDER

Herman Morissey Brown, Huntington, W. Va., assignor to The International Nickel Company, Inc., New York, N. Y., a corporation of Delaware

Application August 26, 1938, Serial No. 226,851

14 Claims.

(Cl. 51—87)

The present invention relates to strip grinders, and, more particularly, to a strip grinder capable of grinding both sides of a strip or sheet of metal to plane surfaces.

5 In the manufacture of sheet and strip having good surface finish, or high surface polish, it is necessary in many instances to grind the surfaces of the sheet or strip to remove surface defects before the last rolling operation. Heretofore the grinding operation has generally been performed on a grinding table on which successive lengths of the strip were ground by a rotating grinding wheel suspended by means of a long connecting rod from an overhead pivot 10 and swung back and forth by the operator along the strip. During grinding the strip lay stationary on a supporting table, being moved only after a length had been finished. Due to the pendulum-like motion of the grinding wheel, the 15 strip had a series of transverse cylindrical concavities on the ground surface each of which abutted, at its lateral boundaries, against adjacent concavities. These concavities were undesirable because of the difficulties experienced 20 in cold rolling the ground strip, particularly in delivering the strip from the cold rolling mill. In carrying out the grinding by this method, moreover, the strip was almost invariably ground thinner at one or both edges than in the middle. 25 As a result, when the ground strip was further rolled the thicker sections were extruded or elongated to a greater extent than the thinner sections, producing a warped and twisted strip.

It is an object of the present invention to provide 30 a strip grinding machine capable of grinding one or both sides of a strip of metal or alloy to substantially uniform and constant gauge throughout its length and width.

It is another object of the invention to provide 35 a strip grinding machine capable of grinding a plurality of strips simultaneously, regardless of their widths and thicknesses.

A further object of the invention contemplates the provision of a strip grinding machine which is 40 practically automatic in operation, which is simple yet sturdy and reliable in operation, and which can be manufactured and operated at relatively low cost.

Other objects and advantages of the present 45 invention will become apparent from the following description, taken in conjunction with the drawings, in which—

Fig. 1 represents a somewhat schematic side 50 elevational view of a portion of the apparatus

embodimenting the present invention, certain parts being in section;

Fig. 2 shows the remainder of the apparatus, likewise in side elevation and with certain parts in section;

Fig. 3 is a sectional view along the line 3—3 of Fig. 1 illustrating one form of the mounting of the grinding wheel and the backing-up wheel;

Fig. 4 depicts the structure looking to the left of Fig. 3 along the line 4—4; and

Fig. 5 is a view similar to Fig. 3 illustrating another embodiment of the invention having a different arrangement of the grinding wheels.

Generally speaking, a strip grinder embodying my invention comprises one or more grinding wheels and one or more backing-up wheels rotating in fixed but adjustable journals, and means for feeding the strip between the said grinding wheel or wheels and backing-up wheel at a controllable speed, the novel arrangement of parts effectively overcoming the defects of prior art grinding machines and yielding a ground strip having substantially uniform gauge throughout its longitudinal and cross-sectional dimensions.

Referring more particularly to Figs. 1 and 2, it will be seen that an improved grinder embodying the present invention may comprise a coil box 10, a top surface grinder 12, a bottom surface grinder 14 and a strip coiler 16. The strip 18 to be ground is placed in coiled form in the coil box 10 and the outer end is passed through the top surface grinder 12 where the top surface is ground, then through the bottom surface grinder 14 where the bottom surface is ground, and finally to the strip coiler 16 where it is recoiled. The ground strip may thereafter be cold rolled to finished gauge as those skilled in the art will readily understand. Alternatively a single grinder 12 or 14 could be used and after grinding one side, the strip could be turned over and run through a second time to grind the surface left unground in the first pass.

The coil box 10 is of conventional structure and is designed merely to hold the coil of strip so that it may be uncoiled smoothly, uniformly and without difficulty.

The top surface grinder 12 comprises a housing 20 having a base 22, two standards or housings 24 with windows 26 adapted to receive the journals for a pair of shafts 28 and 30, and a top frame member 32. The pair of shafts 28 and 30 carry a grinding wheel 34 and a backing up wheel 36, respectively, in a manner hereinafter described. The journals for shaft 28 are vertically adjustable by means of the adjusting rod

38 to regulate the distance between the grinding wheel 34 and the backing up wheel 36 through which the strip 18 passes to be ground. Shaft 28 is power driven in the direction indicated by 5 the arrow at a controllable speed by a motor (not shown). In order to prevent the strip 18 from being pulled through the machine or torn on account of the grinding action, pinch rolls 40 are provided in advance of the grinding wheel 34, 10 and these rolls 40 are power driven at a controllable speed by a motor (not shown). The motor for driving the pinch rolls 40 may be the same motor that drives the grinding wheels or a separate motor. In either case the grinding 15 wheel rotates at a considerably higher peripheral speed than the pinch rolls and the pinch rolls 40 feed the strip 18 at the proper speed to the grinding wheels while maintaining the strip taut. The strip 18 is absolutely under control of the operator at all times. Similar pinch rolls 42 are provided at the exit side of the grinding wheel 34 but they need not be power driven. Guide rolls 44 for the strip being ground are mounted on a cross member 46 in advance of the pinch rolls 20 40. Two such guide rolls 44 are used for each strip being ground, one at either side of the strip, and in order to accommodate strips of varying widths and numbers the guide rolls are made adjustable laterally, for example, by providing a 25 slot 48 in the cross member 46 and mounting the rolls 44 on stub shafts held in position by machine screws 50.

The bottom surface grinder 14 is identical with the top surface grinder 12 except that the positions of the grinding wheel 34 and the backing-up wheel are reversed. Corresponding parts are designated by the same reference numerals.

The strip coiler may be of conventional type comprising a framework 52 supporting a wiper 40 54, feed rolls 56 and a coil housing 58.

The shaft 28 is preferably long enough to accommodate a plurality of grinding wheels 34, one of which is shown in Fig. 3. The grinding wheel 34 is made of some suitable abrasive such as 45 silicon carbide particles bonded together in a manner well understood by those skilled in the art. To prevent relative rotation between the shaft 28 and the grinding wheel 34, they are keyed together, as shown in Figs. 3 and 4, by 50 splines 60 running the full length of the shaft 28. Steel or other hard metal plates 62 faced with lead or other soft metal 64 capable of grabbing or gripping into the abrasive materials of the wheel 34 are likewise keyed to the shaft 28 55 by the splines 60 and held tightly against the wheel 34 by spacing collars 66 and retaining collars 68. The latter are secured against movement along the shaft 28 by set screws 70, or the like. This novel arrangement of the grinding 60 wheel 34 and associated parts is of great practical importance in increasing the flexibility of the machine. For example, if a 4-inch strip is to be ground, a 4 inch grinding wheel would be put in place on shaft 28. If a wider or narrower 65 strip was to be ground thereafter, a grinding wheel of corresponding width would be substituted. Similarly, if it were desired to grind several strips simultaneously, whether they were the same width or not, the appropriate grinding 70 wheels 34 would be placed on the shaft 28 and the guide rolls 44 placed in proper position to direct the strips to the respective grinding wheels.

The shaft 30 carrying the backing-up wheel 36 is preferably about the same length as shaft 75 28 and mounted parallel thereto. The backing-

up wheel may be made in semi-circular segments 72 and 74 held together and tightly against shaft 30 by machine screws 76 set in countersunk bores in segment 72, as seen in Fig. 4. Ordinarily, one backing-up wheel is used for each grinding wheel, 5 and the backing-up wheels are adapted to be mounted at any place and in any desired number along the shaft 30 to correspond with the number and size of the grinding wheels being used, as described hereinabove. Preferably the 10 backing-up wheel is slightly thinner than the grinding wheel and narrower than the strip being ground so that the edges of the strip are unsupported, as seen in Fig. 3. For example, in grinding a strip of metal about 6 inches wide 15 and 0.125 thick, the backing-up wheel may be about $\frac{1}{4}$ inch thinner than the grinding wheel whereby a band about $\frac{1}{2}$ inch wide is left unsupported along each edge of the strip. The width of the unsupported band may vary with 20 the thickness, composition, heat treatment, etc., of the strip being ground, as those skilled in the art understand. By thus leaving the edges of the strip unsupported the difficulty experienced with prior art grinding machines of grinding the edges 25 thinner than the body of the strip is completely overcome. It will, of course, be understood that the bottom surface grinder 14 is provided with grinding wheels 34 and backing-up wheels 36 the same as top surface grinder 12, except that their 30 respective positions are reversed with respect to the strip.

The improved grinder embodying the present invention may also be used simultaneously to 35 grind strips having different gauges by choosing grinding and backing-up rolls of different diameters. The pinch rolls 40 and 42 in such case, are provided with removable wheels or drums having varying outside diameters to accommodate strips of different thicknesses. Similarly, 40 the wheels and pinch rolls may be shaped to accommodate various shapes such as flats, half rounds, hexagons, rounds, etc.

A modified arrangement of grinding wheels 45 is shown in Fig. 5 in which the backing-up wheel is replaced by a grinding wheel and two spaced grinding wheels are used on the upper surface. In this embodiment of my invention, the shafts 28 and 30 are both power driven and the grinding wheels on one shaft serve also as backing-up 50 wheels for the grinding wheels of the other shaft of the same pair. The two upper grinding wheels are spaced apart on their common shaft a distance practically equal to the thickness of the lower grinding wheel. As a result, the strip is ground at the center or central regions on the lower surface and at the edges or outer regions on the upper surface. After passing through the grinder once the strip may be turned over 55 and run through again in order to grind the surfaces left unground in the first pass. Alternatively grinders 12 and 14 may be employed in tandem, the bottom grinder 14 being provided with three complementary grinding wheels to 60 grind the center of the top surface and the edges of the bottom surface whereby the strip is ground on both surfaces in a single pass. The embodiment of my invention illustrated in Fig. 5 is not restricted to the use of the two-over-one grinding wheel arrangement but may be applied with 65 grinding wheel combinations of three-over-two, four-over-three, etc., as well as one-over-two, two-over-three, etc. The characteristic feature of the embodiment of the invention illustrated in Fig. 5 is that the grinding wheels for grinding 70

one surface of the strip are arranged in spaced relation along their common shaft, whereas the grinding wheels for grinding the other surface of the strip are arranged along their common shaft opposite the spaces between the grinding wheels for grinding the first mentioned side of the strip. The result is that the strip is ground in narrow staggered bands running along both surfaces of the strip. This staggered arrangement of grinding wheels may be used without oppositely placed backing-up wheels in grinding strip exceeding about 0.062 inch in thickness. The width of the unsupported bands of the strip, i. e. the distance between adjacent grinding wheels may vary depending upon the thickness, composition and heat treatment of the strip being ground, and upon the distance between the grinding wheels and the pinch rolls 40 and 42, as those skilled in the art will readily understand. For example, when the distance between the points of contact of the pinch rolls 40 and the grinding rolls 34 with the strip was about 18 inches, a strip of metal about 0.125 of an inch thick and 12 inches wide was ground with grinding wheels about 4 inches thick mounted in the two-over-one arrangement of Fig. 5. The unsupported band at each edge of the strip was about 4 inches wide on either side of the single grinding wheel 34. The strip was turned over and passed through a second time to grind the bands left unground in the first pass. About 0.0015 of an inch of metal was ground off in each pass at a rate of about 22 feet per minute. The ground strip had satisfactory uniformity of thickness in both cross and longitudinal section and was cold rolled to finished gauge without warping or distortion. An advantage of the staggered grinding wheel arrangement illustrated in Fig. 5 over the solid wheel arrangement of Fig. 3 is that a heavier grind on the strip may be taken without the usual buckling that would occur if it were attempted to remove the same amount of metal from a strip of the same width at the same speed with a solid wheel regardless of the type of support used to back up the strip.

Although this present invention has been described in connection with specific embodiments, modifications and variations may be resorted to, as those skilled in the art will understand. For example, a backing-up wheel similar to 36 in Fig. 4 could be used in place of the lower grinding wheel 34 of Fig. 5, and by using machines in tandem as fully described hereinabove, the strip may be ground in a single pass. Such variations and modifications are to be understood as coming within the scope of the invention as hereinabove described and set forth in the appended claims.

I claim:

1. A strip grinding apparatus comprising means for holding a coil of strip to be ground, a top surface grinder, a bottom surface grinder, and means for recoiling the ground strip, said surface grinders comprising standards having vertically adjustable journals, two pairs of shafts rotatably mounted in said journals, one of the shafts of each pair having a plurality of grinding wheels mounted in spaced relation thereon and the other shaft of each pair having one less grinding wheel than the first mentioned shafts, the said grinding wheels being arranged in staggered relation on each pair of shafts and with the shaft having the larger number of grinding wheels arranged to grind the top of the strip on one pair of shafts and the bottom of the strip

on the other pair of shafts, means including steel plates faced with lead at either side of each grinding wheel to position and maintain the grinding wheels in fixed but adjustable position on said grinding wheel shafts with the distance from the outside faces of the outside grinding wheels on the shaft having the larger number of grinding wheels corresponding to the width of said strip whereby the edges of the strip are left unsupported during grinding, pinch rolls rotatably mounted in said standards at either side of each pair of shafts, and means to drive the grinding wheel shafts and the pinch rolls at controllable speeds, and laterally adjustable guide rolls mounted in advance of the grinding wheels and adapted to direct the strip to the grinding wheels.

2. A strip grinding apparatus comprising a top surface grinder and a bottom surface grinder, said surface grinders comprising standards having vertically adjustable journals, two pairs of shafts rotatably mounted in said journals, one of said shafts of each pair having a plurality of grinding wheels mounted in spaced relation thereon and the other shaft of each pair having one less grinding wheel than the first mentioned shafts, the said grinding wheels being arranged in staggered relation on each pair of shafts and with the shaft having the larger number of grinding wheels arranged to grind the top of the strip on one pair of shafts and the bottom of the strip on the other pair of shafts, means including steel plates faced with lead at either side of each grinding wheel to position and maintain the grinding wheels in fixed but adjustable position on said grinding wheel shafts with the distance from the outside faces of the outside grinding wheels on the shaft having the larger number of grinding wheels corresponding to the width of said strip whereby the edges of the strip are left unsupported during grinding, pinch rolls rotatably mounted in said standards at either side of each pair of shafts, means to drive the grinding wheel shafts and the pinch rolls at controllable speeds, and laterally adjustable guide rolls mounted in advance of the grinding wheels and adapted to direct the strip to the grinding wheels.

3. A strip grinding apparatus comprising two pairs of shafts, means for rotatably mounting said shafts, one of the shafts of each pair having a plurality of grinding wheels mounted in spaced relation thereon and the other shaft of each pair having one less grinding wheel than the first mentioned shafts, the said grinding wheels being arranged in staggered relation on each pair of shafts and with the shaft having the larger number of grinding wheels arranged to grind the top of the strip on one pair of shafts and the bottom of the strip on the other pair of shafts, means to drive the grinding wheel shafts at controllable speeds and means for feeding the strip to the grinding wheels at the proper speed.

4. A strip grinding apparatus comprising a pair of shafts, means rotatably mounting said shafts in parallel relation, one of said shafts having a plurality of grinding wheels mounted in spaced relation thereon with the distance from the outside faces of the outside grinding wheels corresponding to the width of the strip to be ground, the other of said shafts having one less grinding wheel than the first mentioned shaft, the grinding wheels on the second mentioned shaft being mounted thereon opposite the spaces between the grinding wheels on the first mentioned shaft, means to drive the grinding wheel shafts

at controllable speeds, and means for feeding the strip to the grinding wheels at the proper speed.

5. A strip grinding apparatus adapted simultaneously to grind a plurality of strips of metal comprising a pair of shafts, means rotatably mounting said shafts in parallel relation, one of said shafts having a plurality of grinding wheels mounted thereon, the other of said shafts having a like plurality of backing-up wheels mounted thereon, said shafts being adjusted to provide a space between each grinding wheel and associated backing-up wheel slightly less than the thickness of the strip to be ground, a pair of 15 guide rolls in advance of each grinding wheel adapted to direct the strips to the spaces between the grinding wheels and their associated backing-up wheels so that both edges of the strips extend laterally beyond the backing up 20 wheels, and means for feeding the strips to the grinding wheels at the proper speed.

6. A strip grinding apparatus comprising a first rotatable grinding means adapted to grind spaced bands running along one surface of a strip of metal to be ground, a second rotatable grinding means adapted to grind the other surface of said strip opposite the bands left unground by said first grinding means, means to adjust the distance between the grinding means on opposite sides of 25 the strip, and means for producing relative motion between the strip and the grinding means longitudinally of the strip whereby the strip is progressively ground.

7. A strip grinding apparatus comprising a first grinding means adapted to grind spaced bands running along one surface of a strip of metal to be ground, a second grinding means adapted to grind the other surface of said strip opposite the bands left unground by said first grinding means, and means for producing relative motion between the strip and the grinding means longitudinally of the strip whereby the strip is progressively 30 ground.

8. A method of grinding a metal strip comprising progressively supporting the strip opposite the area being ground only at points inwardly from the edges whereby a band along each edge of the strip is unsupported, and progressively grinding the strip including the unsupported bands.

50 9. A method of grinding a metal strip comprising progressively supporting the strip opposite the area being ground only at points inwardly from the edges whereby a band along each edge of the strip is unsupported, progressively grinding spaced bands along the strip including said unsupported bands, and subsequently grinding the bands left unground in the first grinding operation.

10. A method of grinding both surfaces of a metal strip comprising grinding the surfaces in narrow staggered bands running along both surfaces of the strip by means of rotating grinding wheels which mutually support the strip for the grinding wheels on the opposite side, and subsequently grinding the unground bands from the first operation in like manner.

11. In a method of grinding metal strip, the steps comprising progressively grinding at least 10 a portion of one surface of a metal strip including bands extending inwardly from the lateral edges thereof while supporting the metal strip during the grinding operation only inwardly from the edges, the bands at the lateral edges of the 15 strip being without direct support, whereby excessive removal of metal at the edges is prevented.

12. In the production of metal strip of practically uniform gauge in cross section for cold rolling to finished gauge without substantial 20 warping or twisting, the grinding method comprising supporting the strip for the grinding operation only inwardly from the edges whereby a band along each edge of the strip is unsupported, and progressively grinding at least a portion of 25 the surface of the strip including said unsupported bands, whereby ground strip of substantially uniform gauge in cross section is produced.

13. In the process of grinding metal strips by rotating grinding means to produce ground strip 30 of practically constant gauge and cross section adapted for cold rolling to finished gauge without substantial warping or twisting, the method of preventing the grinding off of an excess of metal adjacent to the lateral edges of the strip 35 which comprises applying force to one surface of the strip to bring the other surface thereof into contact with the grinding means, said force being applied only inwardly from the lateral edges, bands adjacent to the lateral edges of the 40 strip being given no direct support at the time the metal is being ground therefrom, whereby ground strip of substantially uniform gauge in cross section is produced.

14. A method of grinding both surfaces of a 45 metal strip comprising progressively grinding at one operation an area substantially equivalent to the area of one surface, said area including only one surface of bands adjacent to the lateral edges of the strip which are without direct support during the grinding operation opposite the place being ground, and subsequently progressively grinding the area left unground in the first operation, including the other surface of the bands adjacent the lateral edges of the strip 50 which are likewise without direct support during the grinding operation opposite the place being ground.

HERMAN MORISSEY BROWN.
